UNITED STATES PATENT OFFICE.

VICTOR E. I. CARLSON AND HERMAN PETERSON, OF CHICAGO, ILLINOIS.

GARMENT-SUPPORT.

1,202,482.

Specification of Letters Patent. Patented Oct. 24, 1916.

Application filed February 16, 1916. Serial No. 78,594.

To all whom it may concern:

Be it known that we, VICTOR EMIL ISIDOR CARLSON and HERMAN PETERSON, citizens of the United States, and residents of the city 5 of Chicago, in the county of Cook and State of Illinois, have invented a certain new and useful Improvement in Garment-Supports; and we do hereby declare that the following description of our said invention, taken 10 in connection with the accompanying sheet of drawing, forms a full, clear, and exact specification, which will enable others skilled in the art to which it appertains to make and use the same.

15 Our invention relates generally to improvements in garment supports, and it consists, essentially, in the novel and peculiar combination of parts and details of construction, as hereinafter first fully set forth 20 and described and then pointed out in the claims.

In the drawing already referred to, Figure 1 is a view of a human figure as wearing our improved shirt waist, shirt, or blouse 25 and its accompanying belt. Fig. 2 is a rear or bottom view of the opposite ends of the belt, and likewise a rear or bottom view of the buckle which adjustably connects the ends of the said belt. Fig. 3 is a cross section of the belt in line 3—3 of Fig. 2. Fig. 4 is a cross section of the buckle in line 4—4 of Fig. 2. Fig. 5 is an edge view of the buckle, parts of said buckle being shown in section, said section being taken in line 5—5 30 of Fig. 2. Fig. 6 is a vertical section, at 6—6 of Fig. 1, on an enlarged scale through a side of our shirt waist at the lower edge thereof, showing the belt in position, said belt being likewise in vertical section. Fig. 35

40 7 is a like section as Fig. 6, including means for preventing the rising of the shirt waist and belt above the waist line or upper edge of a pair of trousers, at the rear of said trousers. Fig. 8 is a similar section disclosing devices to prevent the sliding up of the shirt waist and buckle above the waist line at the front of the trousers. Fig. 9 is a section of the construction at the lower edge 45 of the shirt waist, whereby a sliding interlock with the belt proper is secured, said section being on an enlarged and somewhat 50

distorted scale. Figs. 10, 11, and 12 are similar sections showing the steps required to produce the construction shown in Fig. 9.

Like parts are indicated by corresponding 55 characters or symbols of reference in all the figures of the drawing.

Our invention is particularly intended for the use of men who, for anatomical or physical reasons, cannot support the trousers by means of a waist belt sufficiently tightened, and who are compelled to employ suspenders or like devices to support the trousers; and, who, yet, wish to affect the shirt waist style of dress, without "belting" 60 in" the waist belt, or employing suspenders which are visible.

Our invention, therefore, comprises a shirt or shirt waist, the lower edge of which is intended to project slightly below the 70 waist line of the trousers, but exteriorly of the trousers. And at the lower edge of the shirt waist are provided means for maintaining in sliding interlock, a belt whereby a neat and finished appearance is imparted 75 to the shirt waist. In connection with this belt is a sheet metallic connecting buckle whereby the ends of the belt are adjustably connected together without producing an overlap of the ends of the belt. 80

Referring now to the drawing A indicates the shirt, shirt waist, waist shirt, or blouse as the case may be; B, the belt surrounding the lower edge thereof and, C, the buckle connecting the free ends of the belt, 85 preferably at the front of the shirt. The shirt proper of our invention may be, in general, of typical construction, excepting that it is made tailless; *i. e.* that the lower edge of the shirt extends only about an inch 90 or thereabout below the waist line or upper edge of the trousers, and instead of being tucked into the trousers, projects over the trousers. As a matter of fact, we may convert a typical "tail shirt" into our improved 95 shirt by cutting off the tails at the proper point and applying thereto our improvements as below described.

Assuming that the shirt has been prepared of the proper length as indicated above, we 100 first sew along the lower edge 10, Fig. 10, of the material 11 from which the shirt is

made, inside and outside strips of muslin 12 and 13, after which we double over these strips to conceal the stitching 10^a and to cause the strips to depend from the lower edge of the shirt, and then we stitch these strips 12 and 13 together at their lower edges, as seen at 14, Fig. 11. Next we fold over the lower edges of the strips to produce a doubled over portion 15, Fig. 12, and 5 stitch this portion to the parts 12 and 13 by stitching 17. Parts 12 and 13 are now again doubled as at 18 Fig. 9, and all the folds stitched together by stitching 19. It will thus be observed that by this construction 10 a double reinforced hem is provided at the lower edge of the shirt, and that a continuous groove 20, with its upper end open is formed exteriorly of the shirt and around the same. It will also be observed that at 15 the upper edge of the groove 20 is formed a doubly reinforced wall 22 the thickness of which is the same as hem 21 at the lower end. It is thus evident that strong and substantial surrounding walls for the groove 20 20 are provided and that the said walls may be oscillated, as it were, about the stitching 19, to widen the groove 20 for purposes of ironing the same in the laundry, as easily understood.

30 Entering the groove 20, embracing the thickened hem 21, and passing around the shirt, with its free ends terminating a short distance from abutment at the front of the shirt, is provided our belt B. This belt is 35 made from leather or like material and has its opposite longitudinal edges doubled over as at 25 and 25^a Fig. 2. Upon these doubled over portions are sewn longitudinal flaps 26 and 26^a; in such manner that a longitudinal opening 27 is left between the inner edges of these flaps, and it is now to be explained that in operative condition the flap 26^a is lodged in the groove 20 Fig. 9, and that the flap 26 embraces the hem 21 of 40 said figure, thereby slidably interlocking the belt to the shirt, the parts being so proportioned to permit a slidably endwise movement, when the parts are interlocked.

At the free ends of the flaps 26 and 26^a 45 are fastened sheet metallic tips 28 to stiffen the ends of said flaps and facilitate the proper entrance into position of the said belt.

The free ends E and E', Fig. 2, of the belt 50 B are connected together by a buckle C, and, for connecting purposes the end E of the belt is possessed of a wire loop 30, while the opposite end E' has a transverse wire 31, said wire having heads 32 and 32^a projecting 55 beyond the margins of the belt B.

The buckle C is preferably made of thin sheet metal of rectangular cross sectional contour, the interior dimensions of which buckle are such as to permit the entrance, 60 at one end, of the end E' with its heads 32

and 32^a of the belt B. This buckle is comprised of top and bottom walls 40 and 40^a and edge walls 41 and 41^a. Between the edge walls 41 and 41^a are produced saw teeth 42, with an open slot 43 there above, the walls 41 being spread apart to permit the passage of the heads 32 and 32^a as clearly seen in Fig. 4. At the opposite end of said buckle are formed hooks 50 to embrace the wire loop 30 of the end E of the belt, and we now direct attention to the fact that top wall 40 of the buckle projects beyond the loop 30 to conceal the same from view. Projecting from the bottom wall 40^a is a hook 51, the object of which is to engage a wire or threaded loop 52, Fig. 8, attached to the front of the trousers T, to prevent the belt and shirt from rising above the top of the waist line of the trousers. In like manner there is provided a freely fitting light metallic Z-bar 53, Fig. 7, supported from the belt B and engaging a like loop 54 at the rear of the trousers to retain the belt in proper position.

In operation the belt B is attached to the 90 shirt while in the wearer's hands, after which the shirt is applied to the body over the suspenders and buttoned up in the usual manner. Then end E' is inserted into the buckle C and when enough tension is secured the heads 31 and 32 are permitted to engage the saw teeth 42, in an efficient manner.

It is now to be understood that our invention may be applied to women's waists or 100 shirt waists or children's blouses without change or modification.

We have hereinbefore disclosed the preferred mode of practising our invention, but we reserve the right to make such and any 105 changes as might occur to one skilled in the art to which this invention appertains, or to make any and all such alterations as may be permitted under the doctrine of equivalents.

We claim:

1. A shirt including a shirt body, having a thickened lower margin and a continuous open groove between said shirt body and said margin, and a belt, said belt having longitudinal flaps engaging said groove and 115 said margin.

2. A shirt including a shirt body, an upwardly projecting portion extending the entire length of said shirt body, said portion having its lower edge stitched to said shirt 120 body, there being an open top groove between said portion and said shirt body, and a belt, said belt having longitudinal, reentrant flaps, one of said flaps being lodged in said groove and the other of said flaps embracing the lower edge of said shirt body.

3. A shirt including a shirt body having a lower edge, material attached near said lower edge and depending therefrom, surrounding said shirt body, a thickened hem 130

at the lower edge of said material, a thickened hem at the upper, free edge of said material, there being an open top groove between said thickened hem and the exterior 5 of said shirt, a belt, said belt having reentrant marginal flaps, one of said flaps being lodged in said groove and the other of said

flaps embracing the lower thickened edge of said material.

In testimony that we claim the foregoing 10 as our invention, we have hereunto set our hand.

VICTOR E. I. CARLSON.
HERMAN PETERSON.
